CLAIM

I claim the ornamental design for a fabric, as shown and described.

DESCRIPTION

FIG. 1 is a perspective view of a fabric showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view.

The dot dash dot broken lines define the boundaries of the claim and form no part thereof.

1 Claim, 5 Drawing Sheets(56)
